US00D924475S

(12) **United States Design Patent** (10) Patent No.: **US D924,475 S**
(45) Date of Patent: **** Jul. 6, 2021**

(54) **E-CIGARETTE**

(71) Applicant: **Xuanwen Ouyang**, Guangdong Province (CN)

(72) Inventor: **Xuanwen Ouyang**, Guangdong Province (CN)

(**) Term: **15 Years**

(21) Appl. No.: **29/714,544**

(22) Filed: **Nov. 25, 2019**

(30) **Foreign Application Priority Data**

Nov. 7, 2019 (CN) 201930612362.X

(51) **LOC (13) Cl.** **27-02**

(52) **U.S. Cl.**

USPC **D27/162**

(58) **Field of Classification Search**

CLAIM

The ornamental design for an E-cigarette, as shown and described.

DESCRIPTION

Fig. 1 is a front elevational view of an E-cigarette showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof; and,

FIG. 8 is an exploded view thereof.

The broken lines shown illustrate parts of the E-cigarette that form no part of the claimed design.

1 Claim, 5 Drawing Sheets
